UNITED STATES PATENT OFFICE

2,682,975

DUMPING BOX WITH HINGED BOTTOM
HAVING DRIP CATCHING MEANS

Frank H. Stoner, Monroe, Mich., assignor to Monroe Auto Equipment Company, Monroe, Mich., a corporation of Michigan

Application July 12, 1949, Serial No. 104,309

8 Claims. (Cl. 222—108)

1

This invention relates to a dumping box structure and more particularly to a dumping box structure incorporating means for preventing fluid from leaking therefrom, and it is an improvement over the copending patent application of Brouwer D. McIntyre et al. for improvements in Dumping Box, Serial No. 11,536, filed February 27, 1948, now Patent No. 2,596,903, dated May 13, 1952.

The aforementioned copending patent application illustrates generally a dumping box structure of the type having a bottom closure pivotally connected with a box portion adjacent the rear wall thereof for swinging movement toward and away from the box and incorporating novel latch means for holding the bottom closure in its upwardly swung closed position, which means are releasable to permit the bottom closure to swing downwardly to an open dumping position. A supporting structure is illustrated in the application for supporting the box portion on a supporting surface, whereby to permit the entrance of the fork of a lift truck between the supporting surface and the bottom closure so that the bottom closure can be swung into its upwardly swung closed position by means of a lift truck fork or platform. Means are also illustrated in this copending application to permit the box to be swung to its upwardly closed position by overhead devices such as a crane or the like. A supporting stand is also illustrated for supporting the box and for providing a chute and tray into which material from the box may be dumped.

When a box of the type illustrated in the aforementioned copending application is filled with, for example, metal parts which have been dipped in or coated with fluid, such as oil, the oil flows off the parts and works its way toward the bottom closure. Even when the bottom is closed, the fluid tends to leak out of the box structure and drip on the floor, thus, of course, creating a messy condition, as well as a hazardous condition in an industrial plant.

The principal object of this invention is, therefore, to provide a dumping box structure of the aforementioned type, in which means are provided for making the dumping box structure fluid tight and preventing fluids from escaping from the box structure and dripping onto the floor. It should, however, be noted that the dumping box is not adapted to be completely filled with fluid, but is arranged to handle fluid which may drip off or escape from parts which are carried in the box.

If it is a still further object of this invention to provide in a dumping box structure of the afore-

2

mentioned type, a novel pan arrangement which is connected to the bottom closure for swinging movement therewith and which is constructed so that when the bottom closure is dropped, fluid will be directed from one end thereof and will not spill indiscriminately over the floor or supporting surface.

It is a still further object of this invention to provide in a dumping box structure of the aforementioned type novel pan means which are so arranged as to encompass the bottom closure, but still permit the latch means for the bottom closure to be easily actuated.

It is a still further object of this invention to provide in a dumping box of the aforementioned type, novel baffle means for insuring that all fluids in the box will be directed into the pan means and cannot escape around the edges of the bottom closure.

These and other objects of this invention will become apparent from the following detailed description, taken in conjunction with the accompanying drawing, in which:

Figure 1 is a side elevational view of the dumping box of this invention;

Fig. 2 is a fragmentary front elevational view of the structure illustrated in Fig. 1;

Fig. 3 is an enlarged sectional view of the structure illustrated in Fig. 1, taken along the line 3—3 thereof;

Fig. 4 is a fragmentary longitudinal sectional view of the structure illustrated in Fig. 1;

Fig. 5 is a reduced side elevational view of the pan of this invention;

Fig. 6 is an enlarged fragmentary sectional view of the structure illustrated in Fig. 4, taken along the line 6—6 thereof; and

Fig. 7 is a side elevational view of the structure illustrated in Fig. 1, mounted on a supporting stand, with the bottom closure in its downwardly swung open position.

Referring now to the drawing, it will be seen that a dumping box 9 is illustrated, which is generally similar to the dumping box described in detail in the aforementioned copending patent application, and is preferably formed with corrugated metal walls having an upper beaded edge 11. The bottom closure of the box 9 is indicated at 13 and is preferably made of corrugated sheet metal reinforced by a plurality of longitudinally spaced, generally U-shaped cross members 15, which are welded or otherwise suitably secured to the bottom of the closure. The closure 13 is pivotally connected with the box portion 9, adjacent the rear wall thereof, by means of pivot pins 17, mounted in a supporting leg structure

19. The supporting leg structure 19 supports the box 9 in an elevated position above a supporting surface or a supporting stand, and comprises runner-like legs 21 preferably formed of structural members of generally U-shaped cross section. The upper ends of legs 21 are welded or otherwise suitably secured to the under side of the box 9 on each side of the bottom closure 13. Side plates 23 are secured to the box and supporting legs 21 below the bottom closure 13 and have an inclined lower edge, as can be seen in Fig. 1. The side plates 23 cooperate with the bottom closure 13, when the latter is in its downwardly swung open or dumping position, to form a laterally enclosed chute, down which elements or material, carried within the box 9, may slide.

In order to releasably retain the bottom closure 13 in its upwardly swung closed position, latch means are provided which include a pair of laterally spaced spring pressed plungers 25, which are slidably supported in and extend through apertures in the bottom closure front cross member 15. The spring pressed plungers 25 are interconnected by means of a connector plate 29, which ties the two plungers together for coordinated movement. The outer ends of each of the spring pressed plungers 25 are tapered and are adapted, when the bottom is in its closed position, to project through apertures in latch plates 31, which are welded or otherwise suitably secured to the front wall of the box portion 9.

The front cross member 15 of the bottom closure is provided with a central aperture 33, over which is welded or otherwise suitably secured a guard or bracket 35. A pin 37 is connected at one end to the connector plate 29 and the opposite end thereof extends outwardly through the aperture 33 into the confines of the guard or bracket 35. By inserting a tool 39 (Fig. 7) into the space between the guard 35 and the front end of the pin 37, the pin can be moved rearwardly so as to move the spring pressed plungers rearwardly away from the latch plates 31 and permit the bottom closure to drop down. When the bottom closure is raised to its uppermost position, the plungers 25 will cam over the lower ends of the latch plates 31 and will compress their springs until they come into alignment with the apertures in the latch plates, at which time the springs will move the plungers 25 into the latch plate apertures, so as to releasably retain the bottom closure in its upwardly swung closed position.

In order to prevent fluid, such as oil or the like, which may be on the elements or material carried in the box portion 9, from escaping past the bottom closure onto the supporting surface or floor, a pan 41 is provided, which includes a substantially flat bottom portion 43, vertically extending side wall portions 45, a front wall portion 47 and a rear wall portion 49. In the illustrated embodiment the pan has a capacity of only about one-third of the box capacity, although this ratio may be varied without departing from the invention. The pan is, therefore, designed primarily only to catch and retain fluid which drips from parts or elements in the box. The upper surface of the pan bottom wall 43 is placed against the under side of the bottom closure cross members 15 and the side wall portions 45 extend up along the opposite sides of the bottom closure 13, between the bottom closure and the runner-like legs 21. The upper edges of the side walls 45 are disposed above the

5 top surface of the bottom closure 13. The rear wall 49 extends up along the rear edge of the bottom closure in substantially the same manner. The front wall 47 of the pan 41 is spaced 10 outwardly or forwardly of the front edge of the bottom closure 13, and outwardly of the latching mechanism guard or bracket 35. A laterally extending inwardly projecting flange 53 is provided along the upper edge of the front wall 47, and the flange terminates at its inner end adjacent 15 to the front wall of the box portion 9. The flange 53, as can be seen in Fig. 6, is centrally recessed or notched out at 55, so as to permit the tool 39 to be inserted between the front wall of the latching mechanism guard 35 and the pin 37 for 20 releasing the latching mechanism and permitting the bottom closure to drop down to its dumping position. At the same time, the recess or notch 55 provides an outlet opening through which fluid in the pan may be discharged, as will hereinafter appear. The flange 53 is also recessed at 56, adjacent each end thereof, to provide clearance for latch plates 31. The pan 25 41 is connected to the bottom closure 13 for swinging movement therewith, by any suitable means such as welding, and by means of the pivot pins 17, which pivotally connect both the bottom closure and the pan to the box portion 9 and supporting structure 19.

In order to insure that any liquid in the box portion 9 will be directed into the pan 41, baffle plates 59 are provided in the box portion, which extend angularly along each side wall of the box portion, from the front to rear thereof, so that the upper edge of each engages the side wall of the box above the box bottom and the lower edge thereof overlaps the side wall portions 45 of the pan 41 and abuts the upper surface of the bottom closure 13, when the latter is in its upwardly swung closed position. Each baffle plate 35 59 is secured to the side and bottom wall portions of the box 9, outwardly of the bottom closure 13, by means of a plurality of braces 61, which are secured to the baffle plates 59 and to side and bottom wall portions of the box in any suitable manner, such as by welding. Therefore, any liquid in the box portion 9 will be directed onto the bottom closure of the pan 41 and will not escape or leak from the box portion except into 40 the pan 41.

The supporting structure 19 supports the box far enough above a supporting surface to permit the fork of a lift truck or the like to be inserted 55 between the supporting surface and the under side of the pan and bottom closure, so that the lift truck fork can swing the bottom closure and pan to their upwardly swung closed position and at the same time lift the entire dumping box structure for transport to any suitable place, 60 such as a supporting stand 65, illustrated in Fig. 7. The supporting stand 65 includes legs 67 and a top frame 69. A portion of the top frame 69 projects forwardly of the leg structure 67 to provide in effect a forwardly projecting ledge or shelf-like frame structure 71, including side walls 73, a front end wall 75, and a bottom wall 76.

When the dumping box is mounted on the supporting stand 65 the runner-like legs 21 are supported on the top frame 69 so that the bottom closure 13 and pan 41 are disposed in a plane above that of the forwardly projecting frame structure 71. When the bottom closure 13 is released, it will pivot downwardly to its dumping position and the side plates 23 of the box will cooperate with the side plates 73 of the

supporting stand to provide a laterally enclosed chute which is open at the front end thereof, so that material or elements within the dumping box will slide along the inclined drop bottom 13 and into the top frame structure 71 between the side walls 13 and front wall 75. The material sliding down the bottom closure can spill over the horizontal flange 53 on the front of the pan 41 and any liquid in the pan will be discharged into the shelf frame structure through the recess or notch 55. In this way both the material in the box, as well as any liquid in the pan can be easily removed therefrom.

It will thus be appreciated that the pan 41 will catch and retain any fluid which may be on the parts or in the box portion 9, when the bottom closure is in its upwardly swung closed position and such liquid will not spill out of the box onto the floor or supporting surface so as to create a messy, as well as hazardous, condition in industrial plants. At the same time, it will be appreciated that the pan does not interfere with the operation of the bottom closure in permitting material to be dumped therefrom, as described above. It will furthermore be appreciated that the pan does not interfere with the lifting of the dumping box structure by the fork of a lift truck or by means of a crane-like structure, if the box is adapted for actuation by such a device, as illustrated and described in the aforementioned copending application. The pan 41 is also of a relatively simple construction and of a construction which permits easy connection thereof to the bottom closure. The structure of this invention thus provides a dumping box which will retain liquids therein and which will operate in a satisfactory and efficient a manner as dumping boxes which have been devised heretofore, which would not hold or contain liquids.

What is claimed is:

1. A self-contained dumping box structure including a box portion, a bottom closure for said box portion pivotally connected to said box for swinging movement toward and away therefrom, supporting structure connected to said box for supporting the same above a supporting surface, means for releasably retaining said bottom closure in its upwardly swung closed position, pan means connected to and movable with said bottom closure and including interconnected vertical walls extending completely around and above the upper surface of said bottom closure, so as to prevent fluids in said box from escaping therefrom onto a supporting surface.

2. A self-contained dumping box structure including a box portion, a bottom closure for said box portion pivotally connected to said box for swinging movement toward and away therefrom, supporting structure connected to said box for supporting the same above a supporting surface, means for releasably retaining said bottom closure in its upwardly swung closed position, pan means connected to and movable with said bottom closure and including vertical walls extending above the upper surface of said bottom closure, so as to prevent fluids in said box from escaping therefrom onto a supporting surface, and baffle means in said box for directing any fluid therein into said pan means.

3. A self-contained dumping box structure including a box portion, a bottom closure for said box portion pivotally connected thereto for swinging movement toward and away therefrom, means for releasably retaining said bottom closure in its upwardly swung closed position, pan means connected to and movable with said bot-

tom closure and including substantially vertical side walls laterally enclosing said bottom closure and projecting above the top surface of said bottom closure.

4. A self-contained dumping box structure including a box portion, a bottom closure for said box portion pivotally connected thereto for swinging movement toward and away therefrom, pan means connected to and movable with said bottom closure and including vertical side walls laterally confining said bottom closure and projecting above the upper surface of said bottom closure, said pan means extending forwardly beyond the front end of said bottom closure and being provided with an upstanding front wall, substantially horizontal flange means extending rearwardly from said front wall toward said bottom closure, so as to provide a cover-like portion for said forwardly projecting part of said pan means, whereby when said bottom closure is swung downwardly from said box portion, fluid in said pan means may escape therefrom over said top flange.

5. A self-contained dumping box structure including a box portion, a bottom closure for said box portion pivotally connected thereto for swinging movement toward and away therefrom, supporting structure including a pair of runner-like legs connected to said box portion for supporting the same above a supporting surface, said runner-like legs being disposed on opposite sides of said bottom closure so that said bottom closure is movable therebetween, means for releasably retaining said bottom closure in its upwardly swung closed position, pan means connected to and movable with said bottom closure and including vertical walls extending upwardly from the bottom of said pan means between said runner legs and said bottom closure, with the upper edges thereof disposed above the top of said bottom closure so as to prevent fluids in said box from escaping therefrom onto the supporting surface when the box is in its upwardly swung closed position.

6. A self-contained dumping box structure including a box portion, a bottom closure for said box portion pivotally connected thereto for swinging movement toward and away therefrom, supporting structure including a pair of runner-like legs connected to said box portion for supporting the same above a supporting surface, said runner-like legs being disposed on opposite sides of said bottom closure so that said bottom closure is movable therebetween, means for releasably retaining said bottom closure in its upwardly swung closed position, pan means connected to and movable with said bottom closure and including vertical walls extending upwardly from the bottom of said pan means between said runner legs and said bottom closure, with the upper edges thereof disposed above the top of said bottom closure so as to prevent fluids in said box from escaping therefrom onto the supporting surface when the box is in its upwardly swung closed position, and plate means extending from front to rear in said box portion between said box portion side walls and the upper portion of said pan means so as to insure that all fluid in said box portion will flow into said pan means, and means securing said plate means to said box portion.

7. A dumping box structure including a box portion, a bottom closure for said box portion, pan means confining said bottom closure, with the bottom of said pan means disposed adjacent 75 to the bottom of said closure means and with the

top edge of the vertical walls of said pan means disposed above the top surface of said bottom closure, means pivotally connecting both said pan means and said bottom closure to said box portion for swinging movement toward and away therefrom.

8. A dumping box structure including a box portion, a bottom closure for said box portion, pan means confining said bottom closure, with the bottom of said pan means disposed adjacent to the bottom of said closure means and with the top edge of the vertical walls of said pan means disposed above the top surface of said bottom closure, means pivotally connecting both said pan means and said bottom closure to said box portion for swinging movement toward and away therefrom, and angularly extending baffle means connected to the interior of said box portion and overlapping opposed vertical walls of said pan

means so as to direct any fluid in said box portion into said pan means and prevent the latter from escaping from said dumping box structure.
